UNITED STATES PATENT OFFICE.

YACOUB OHANÉS ZADIGIAN, OF UNION HILL, NEW JERSEY.

SLIP CONSTRUCTION.

Application filed June 10, 1925. Serial No. 36,158.

To all whom it may concern:

Be it known that I, YACOUB OHANÉS ZADIGIAN, a citizen of the United States, and a resident of Union Hill, in the county of Hudson and State of New Jersey, have invented a new and Improved Slip Construction, of which the following is a full, clear, and exact description.

This invention relates to a slip construction. An object of the invention is to provide a simple and efficient flexible slip whereby when boats are being warped into a slip there is no danger of the boat causing the damage to the slip which usually results when the slip, and especially the walls thereof, is rigid.

Another object concerns the provision of means whereby the slip can be located at will in any desired position, and the change in the position of the slip or any part thereof can be readily effected without great expenditure of time, labor or money.

The invention is illustrated in the drawings, of which—

25 Figure 1 is a plan view of a slip having flexible walls; and

Figure 2 is a section through the pontoon forming the wall.

The form of the invention shown in the drawings is a preferred form, although it is understood that modifications in the construction and arrangement of the parts and in the character of the materials used may be adopted without departing from the spirit of the invention as set forth in the appended claims.

The invention in general comprises forming a portion of a slip, for example, the walls thereof, of a series of connected pontoons anchored in a suitable manner to the bottom of the river.

The preferred form of the invention is shown in the drawings, in which Figure 1 represents a dock 10, and 11 represents a series of pontoons which extend out in parallel lines from the dock and preferably form walls or piers therefor. These pontoons float on the water and are preferably connected by any suitable means such as chains 12. These pontoons are preferably made of wood, although any other suitable material can be used. Each pontoon is preferably anchored to the bottom 13 by any

suitable means, such as an anchor 14 and a chain 15. As shown in Figs. 1 and 2, these chains 15 preferably extend up on each side of the pontoon through grooves 12^a, and at the top are connected to a weight element 16. The length of the chain 15 connecting the pontoons with the anchors is determined by the depth of the water and also by the degree of flexibility which it is desired to give to the wall construction. If these pontoons are connected by short chains to each other and to the bottom, the construction will be less flexible than if the connections were longer. The pontoons are preferably of considerable bulk and heavy so that they will have sufficient inertia to act as flexible guiding means for boats which are being warped into their slips. By providing the connecting weight elements 16 at the top it will be possible to repair the connections and to manipulate the chains and anchors from the top of the pontoon.

What I claim is:—

1. A slip construction which comprises a plurality of separate pontoons independently anchored to the bottom and forming a wall or pier of the slip, and a flexible means connecting adjacent pontoons.

2. A slip construction which comprises a plurality of separate floating pontoons, each anchored to the bottom independently of the other and acting as a flexible wall in the warping of boats into their slips and a flexible means connecting adjacent pontoons.

3. A slip construction which comprises a series of floating interconnecting pontoons, each pontoon connected to the bottom to an anchor, through the intermediary of a chain, the chain extending upwardly on each side of each pontoon through slots formed in the sides of the pontoon and connected at the top to an anchor bolt.

4. A slip construction which comprises a series of floating interconnecting pontoons, each pontoon connected to the bottom to an anchor, through the intermediary of a chain, the chain extending upwardly on each side of each pontoon through slots formed in the sides of the pontoon and connected at the top to an anchor bolt, and flexible means connecting adjacent pontoons.

YACOUB OHANÉS ZADIGIAN.
